UNITED STATES PATENT OFFICE.

PETER J. SHRUM, OF MONACA HEIGHTS, PENNSYLVANIA, ASSIGNOR TO COLONA MANUFACTURING COMPANY, OF PITTSBURGH, PENNSYLVANIA, A CORPORATION OF PENNSYLVANIA.

METHOD OF RECLAIMING PIPE COUPLINGS AND THE LIKE.

Application filed June 10, 1924. Serial No. 719,124.

At the present time when a pipe coupling or thread protector becomes damaged to such an extent that it is no longer serviceable, as when the threads thereof have become stripped or otherwise mutilated, it is customary to discard the coupling or protector. The present invention provides a method whereby such damaged couplings and protectors can be reclaimed and made fit for further service, thereby enabling the user of such devices to effect a considerable saving.

The invention is illustrated in the accompanying drawings, in which:

Figure 1 is a view in side elevation, partly broken away, of a half coupling having its threads damaged to such an extent that it is no longer serviceable;

Figure 2 is a plan view of the coupling shown in Figure 1;

Figure 3 is a sectional view of a portion of a press provided with stationary and movable dies and showing the coupling illustrated in Figure 1 in position in the stationary reducing die resting on another coupling which has been forced nearly all the way through the die by a previous operation of the movable die;

Figure 4 is a view similar to Figure 3, but showing the coupling forced part way through the reducing die; and

Figure 5 is a vertical sectional view of the reclaimed coupling.

In the drawings I have illustrated my invention in connection with the reclaiming of a damaged half coupling, but it will be understood that the invention is equally applicable to the reclaiming of full couplings, thread protectors and similar devices.

In Figures 3 and 4 there is shown a portion of a press of suitable construction for carrying out the first step of my method. This press comprises a bed plate 2 having a die holder 3 secured to the upper face thereof by bolts 4. The bed plate and die holder have a circular opening 5 therethrough.

Secured to the upper face of the die holder by the screws 6 is the reducing die 7, preferably made from tool steel. This die is in the form of a ring, the upper portion 8 of the bore of which has a diameter slightly greater than the external diameter

of the coupling 9 shown in Figures 1 and 2 to provide a small amount of clearance. The lower portion 10 of the bore is of reduced diameter, and the portions 8 and 10 are connected by the inclined wall 11. The vertical wall of the portion 8 of the bore has its upper end flared outwardly as indicated at 12 to facilitate the positioning of the coupling in the die.

The plunger 13 of the press has secured to its lower end by the screws 14 a die 15 for cooperation with the reducing die 7. The external diameter of the die 15 is the same as the external diameter of the coupling 9 shown in Figures 1 and 2. The upper die 15 has in its lower face a peripheral groove 16, the outer edge 17 of which is coincident with the peripheral wall 18 of the die. The upper edge 19 of the coupling engages in this groove when the plunger descends and prevents the upper end portion of the coupling from spreading or flaring outwardly as the coupling is forced through the reducing die.

Figure 3 shows the coupling 9 in position in the upper portion 8 of the reducing die and the movable die 15 out of engagement with the coupling. The lower end of the coupling is in engagement with the upper end of another coupling C which has been forced nearly all the way through the stationary die by a previous operation of the movable die. It will be apparent that the movable die cannot force a coupling entirely through the reducing die at one operation by reason of the fact that the diameter of the movable die is greater than the diameter of the lower portion 10 of the reducing die. When the movable die 15 is brought into engagement with the upper edge 19 of the coupling 9 and the latter forced through the reducing die, as illustrated in Figure 4, the coupling C is forced entirely through the stationary reducing die and drops to the floor beneath the bed plate or into a suitable receptacle or onto a conveyor.

Since the diameter of the upper portion 8 of the bore of the reducing die is slightly greater than the external diameter of the coupling to be reclaimed, the latter can be positioned in the portion 8 even though the coupling may have been slightly distorted, thereby losing its truly cylindrical shape. If the coupling has been distorted to such

an extent that it will not readily enter the upper portion 8 of the bore of the reducing die, its lower end will seat in the flared upper end 12 of the bore and when the plunger 13 descends, the coupling will be forced into the portion 8, the lower end portion of the coupling being brought back to its cylindrical shape. As the coupling is forced further through the reducing die, as illustrated in Figure 4, the inclined wall 11 subjects the metal of the coupling to a bending action which not only causes the reduction of the external and internal diameters of the coupling, but tends to break the mutilated threads of the coupling. This breaking of the threads of the coupling facilitates the re-tapping thereof. Not only does the forcing of the coupling through the reducing die reduce the diameter of the coupling, but it also causes a slight increase in the thickness of the wall of the coupling.

After a coupling has been forced entirely through the reducing die the next step is to re-tap it. Any suitable tool may be used for this purpose. The re-tapping operation will completely remove the old mutilated threads and will provide the coupling with new threads, as shown in Figure 5. The coupling may be re-tapped so as to give it the same internal diameter as it originally had or it may have a slightly reduced diameter, enabling it to be used with a pipe of smaller external diameter than the pipe with which the coupling was previously used.

Thread protectors can be reclaimed in substantially the same manner as described for the pipe coupling. No heating of the metal is required, as the process can be carried out as a cold process. Furthermore, pipe couplings and thread protectors which have lost their truly cylindrical shape may be brought to this shape by the reclaiming process described.

It will be seen from the above that the invention provides a simple and relatively inexpensive method whereby pipe couplings and thread protectors which have heretofore been thrown away can be reclaimed.

While I have shown and described a preferred form of apparatus for carrying out my method, it will be understood that changes may be made in the details of construction without departing from the spirit of the invention or scope of the appended claims.

I claim:

1. The method of reclaiming pipe couplings or like articles, which includes pressing on the outer face of the coupling from substantially all radial directions, pressing the metal inwardly to a sufficient degree to break the threads from the article and increase the wall thickness for rethreading while allowing the metal free to flow in a radial direction toward the longitudinal center of the article, and then rethreading the coupling, substantially as described.

2. The method of reclaiming threaded pipe couplings, which includes pressing on the outer face of the coupling from substantially all radial directions while compressing the coupling in a longitudinal direction and pressing the metal inwardly to a sufficient degree to break the threads from the article and increase the wall thickness for rethreading while allowing the metal free to flow in a radial direction toward the longitudinal center of the coupling, and then rethreading the coupling, substantially as described.

3. The method of reclaiming threaded pipe couplings, which includes compressing the coupling in a longitudinal direction and at the same time progressively reducing the inner and outer diameters thereof from end to end to a sufficient degree to break the threads from the coupling and to increase the wall thickness for rethreading without restricting the flow of metal toward the longitudinal center of the coupling, and then rethreading the coupling, substantially as described.

In testimony whereof I have hereunto set my hand.

PETER J. SHRUM.
